UNITED STATES PATENT OFFICE.

DANIEL SULLIVAN, OF ST. LOUIS, MISSOURI.

COIN-CONTROLLED DISPENSING APPARATUS.

SPECIFICATION forming part of Letters Patent No. 757,690, dated April 19, 1904.

Application filed August 15, 1902. Serial No. 119,755. (No model.)

To all whom it may concern:

Be it known that I, DANIEL SULLIVAN, a citizen of the United States, residing at St. Louis, State of Missouri, have invented certain new and useful Improvements in Coin-Controlled Dispensing Devices, of which the following is a full, clear, and exact description, reference being had to the accompanying drawings, forming a part hereof.

10 My invention has relation to improvements in coin-controlled dispensing devices; and it consists in the novel arrangement and combination of parts more fully set forth in the specification and pointed out in the claims.

15 In the drawings, Figure 1 is a top plan of the receptacle with lid swung open. Fig. 2 is a vertical transverse section on line 2 2 of Fig. 1, showing a bonbon-box in the receptacle. Fig. 3 is a view of the operating parts

20 mounted in the rear of the front wall of the receptacle, the cover-plate for said parts being removed, said view showing the first position of the parts or that position in which the lid is held locked. Fig. 4 is a similar view

25 showing second or releasing position. Fig. 5 is an elevation of the rear of the front wall with cover-plate in position, showing application of the key for releasing and ejecting the coin. Fig. 6 is a front elevation of the

30 receptacle. Fig. 7 is an enlarged detail showing application of the ejecting-key to the coin after the lid has been thrown open. Fig. 8 is a section on line 8 8 of Fig. 7, and Fig. 9 is a detail showing the application of the key

35 to the locking-latch.

The present invention is an improvement on the device for which Letters Patent of the United States, numbered 677,748, were granted to me under date of July 2, 1901, and on 40 the device described in my pending application, Serial No. 91,437, filed January 27, 1902, and while contemplating the several objects set forth in both the aforesaid inventions the present device is materially simplified and possesses the additional advantage in that the 45 open position of the locking-latch is independent of the coin, and, further, in that the latch can be set permanently to its open or releas-

ing position even after the coin has been abstracted from the receptacle. 50

It consists in further and other advantages better apparent from a detailed description of the invention, which is as follows:

Referring to the drawings, 1 represents a receptacle having a hinged cover or lid 2, the latter being adapted (under circumstances to be presently referred to) to be swung to an open position by the medial member or arm 3 of a coiled spring 4, coiled about a hinge pin or staple 5, disposed in the upper edge of the rear wall of the receptacle, the free ends of the spring being embedded in said wall. (See dotted representation in Fig. 2.) At the bottom of the receptacle is located an upwardly - curved resilient spring - supporting 65 plate 6, upon which the bonbon-box B rests and which is forced to assume a flat or expanded position when the box has been forced into the receptacle and under the lid thereof when the latter has been closed. The free 70 ends of the spring 6 are provided with slots 7, through which pass the shanks or stems of the guide-pins 8, carried by the bottom of the receptacle, the heads of the pins serving to retain the spring in position. The moment, 75 however, that the lid is released from the locking-latch and has been swung open by the spring 4 the resiliency of the plate 6 forces the box upwardly sufficiently beyond the upper edge of the receptacle, when it may be 80 readily seized by the operator and removed from the receptacle, Fig. 2.

The manner of opening the lid by the introduction of a coin (a dime) is as follows: Mounted along the rear surface of the front wall of 85 the receptacle in front of the cover-plate 9 is a pivoted latch 10, whose medial portion is in permanent engagement with the free end of a flexed spring 11, whose opposite end is fixed to the front wall and whose medial portion 90 bears against a ridge 12, formed on the said wall. When in its normal or locking position, the latch is adapted to engage a catch 13, carried by the free end of the lid, Fig. 3. Between the ridge 12 and a lower ridge 14 is 95 formed a coin-chute 15 for the passage of a

coin introduced into the receptacle through the coin-slot 16 of the lid, (when the latter is closed,) the coin when once introduced being advanced by the arms of a lobed disk 17, carried at the inner end of a spindle 18, operated from the outside of the front wall by a milled head 19. As the coin is thus advanced (see arrows in Figs. 3, 4) it encounters the medial bend of a compoundly-curved latch-controlling lever 20, said bend being below the fulcrum of such lever, and as the coin is thus forced against the bend it tilts the lever 20 sufficiently to cause the upper end thereof to force the latch 10 away from the catch 13, permitting the lid to fly open, as already explained. This tilting of the lever 20 at the same time causes an upward tripping of the free lower end thereof, which end is provided with a tooth or finger 21, normally bearing against a similar tooth 22 at the free end of one arm of a bell-crank or trigger 23, pivoted to the front wall of the receptacle. The trigger 23 is kept in permanent contact with the lever 20 under the resilient action of a spring 24, and as the tooth 21 is thus tripped upwardly the tooth 22 follows it (under the resilient action of the spring 24) and eventually drops behind it, (see Fig. 4,) thus securely locking the lever 20 against any possible return to its normal or first position, the latch 10 under the circumstances remaining permanently in its releasing position, so that no unauthorized person can close and lock the lid after the bonbon-box has once been abstracted, Fig. 4. The coin by this time rests against the base of the trigger, Fig. 4, the rear edge of the coin coming adjacent to the keyhole 25 of the cover-plate 9, Fig. 5.

To remove the coin, the operator inserts the tooth 26 of the key K through the hole 25 behind the coin, rocking the key about the stud 27, thus forcing the coin past the trigger 23 to a point opposite the opening 28, formed in the cover-plate, Fig. 5. The coin can then be abstracted by the operator by inserting his finger into the receptacle and drawing the coin along the inclined wall 29 and upward through the top of the receptacle. In thus forcing the coin past the trigger by means of the key the trigger is tilted back to its normal position, the bent lever 20 being at the same time permitted to resume its normal position under the action of the flexed spring 11, thus permitting the locking-latch to resume its normal or locking position, the parts being ready for the next operation upon the introduction of a fresh bonbon-box into the receptacle. (See dotted position of parts in Fig. 4.) By "normal" or "locking" position of course is meant that position of the locking-latch which permits the same to engage the catch on the lid when the latter is closed.

Should the operator not have a fresh box

of bonbons handy to insert into the receptacle when the latter is exhausted and the occasion should thus arise to leave the lid open indefinitely, so that no unauthorized person should close the lid on an empty receptacle after the coin was removed by the operator, the latter can by inserting the tooth of the key through an opening 30 in the upper edge of the front wall, Fig. 9, force back the locking-latch to an open or releasing position, at the same time bearing down and rocking the lever 20 to its second position, whereupon the parts will be set as shown in Fig. 4, thus permitting the lid to remain open indefinitely. To restore the parts to their locking position, Fig. 3, the operator can then simply run a coin through the device, forcing the coin past the trigger, as already explained, when the several parts will resume their normal positions, as already indicated.

It is apparent, of course, that I may depart from the details here shown without affecting either the nature or spirit of my invention. The lever 20 is limited in one direction by a pin 31.

Having described my invention, what I claim is—

1. In a coin-controlled dispensing device, a suitable receptacle, a spring-actuated lid hinged to the same, a catch carried by the lid, a spring-controlled latch pivoted to the front wall of the receptacle, a spring-controlled pivoted trigger having two arms carried by the front wall of the receptacle, a terminal tooth carried by the upper arm of the trigger, a latch-controlling lever pivoted intermediate the trigger and the latch and having a terminal tooth normally engaging the tooth on the trigger, a rotatable spindle located in advance of the lever, a lobed disk secured to the spindle for advancing the coin against the lever, the lever and trigger being oscillated with the advance of said coin and the teeth aforesaid interlocking with said oscillation, a coin-chute, a coin-slot formed in the lid and registering with the coin-chute, a cover-plate for the several parts, a keyhole being formed in the cover-plate at a point adjacent to the edge of the coin when the latter is resting against the trigger, said keyhole being adapted to receive the tooth of a rotatable key for forcing the coin past the trigger and restoring the parts to their normal position, substantially as set forth.

2. In a coin-controlled dispensing device, a suitable receptacle, a spring-actuated lid hinged to the same, a catch carried by the free edge of the lid, a spring-controlled latch pivoted to the front wall of the receptacle, a bent lever pivoted in proximity to the latch, a rotatable spindle mounted adjacent to the lever, a disk secured to the spindle having a series of arms for advancing the coin against the

lever, a spring-controlled pivoted trigger co-operatively connected with the lever for arresting the lever when the latter has been oscillated by the advance of the coin, the latter being adapted to be subsequently forced against the trigger for restoring the parts to their normal position, a coin-chute, a coin-slot formed in the lid and registering with the coin-chute, the trigger being adapted to arrest

the coin after the latter has been forced past 10 the lever, substantially as set forth.

In testimony whereof I affix my signature in presence of two witnesses.

DANIEL SULLIVAN.
